[57] **CLAIM**

The ornamental design for a set of boat transom swim platform end brackets, substantially as shown and described.

DESCRIPTION

FIG. 1 is a perspective view of a left swim platform end bracket in combination with a right swim platform end bracket which is a mirror image of the left end bracket, both mounted on the transom of a boat, shown in broken lines; also, shown in broken lines between the brackets are strips or stringers; all of said broken lines being shown for illustrative purposes only.

FIG. 2 is a plan view of the left swim platform end bracket shown in FIG. 1;

FIG. 3 is a side elevational view of the outboard side of the left swim platform end bracket shown in FIGS. 1 and 2;

FIG. 4 is a side elevational view of the inboard side of the left swim platform end bracket shown in FIGS. 1 and 2; and

FIG. 5 is an end elevational view of the aft end of the left swim platform end bracket shown in FIGS. 1-4.
